(57) **CLAIM**

The ornamental design for a decorator thermostat cover, substantially as shown and described.

DESCRIPTION

Our invention is an ornamental design for a thermostat cover which is adaptable to harmonize with or accent decorating schemes. Our invention is intended for interior residential or commercial use with a thermostat controlling heating and/or cooling equipment.

FIG. 1 is a perspective view illustrating the front, left side, and top showing our new design for a decorator thermostat cover;

FIG. 2 is a front and lower left perspective view of the decorator thermostat cover where the cover is shown as opaque for clarity;

FIG. 3 is a left side elevational view of the decorator thermostat cover;

FIG. 4 is a right side elevational view thereof;

FIG. 5 is a front elevational view thereof;

FIG. 6 is a top elevational view thereof;

FIG. 7 is a back side elevational view thereof illustrating the removable decorator panel in place;

FIG. 8 is a bottom elevational view thereof;

FIG. 9 is a front plan view of a flat decorator panel removed from the decorator thermostat cover; and,

FIG. 10 is a front plan view of the decorator thermostat cover, shown in an alternate condition of use, illustrating an example wherein wallpaper is affixed to the removable decorator panel and the panel has been reinserted into the cover.
